US0D1093092S

(12) **United States Design Patent** (10) **Patent No.:** **US D1,093,092 S**
(45) **Date of Patent:** **** Sep. 16, 2025**

(54) **CONTAINER**

(71) Applicant: **Helen of Troy Limited**, St. Michael (BB)

(72) Inventors: **Carly Cheng**, New York, NY (US); **Dzmitry Varhan**, Dingmans Ferry, PA (US)

(73) Assignee: **KAZ EUROPE SÀRL**, Bussigny (CH)

(**) Term: **15 Years**

(21) Appl. No.: **29/917,601**

(22) Filed: **Nov. 21, 2023**

(51) **LOC (15) Cl.** **07-09**

(52) **U.S. Cl.**
USPC **D7/602**

(57) **CLAIM**

The ornamental design for a container, as shown and described.

DESCRIPTION

FIG. 1 is a perspective view of a container showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1; and,

FIG. 6 is a top plan view of FIG. 1.

The dash-dot broken lines shown in the figure represent boundaries of the claim that form no part of the claimed design. The dash-dash broken lines shown in the figures represent portions of the container that form no part of the claimed design.

1 Claim, 6 Drawing Sheets
